UNITED STATES PATENT OFFICE.

CHARLES W. POTTER, OF WALTHAM, MASSACHUSETTS.

MANIFOLD-BOOK.

1,382,798.

Specification of Letters Patent. Patented June 28, 1921.

Application filed August 25, 1919. Serial No. 319,612.

To all whom it may concern:

Be it known that I, CHARLES W. POTTER, a citizen of the United States, residing at Waltham, in the county of Middlesex and 5 State of Massachusetts, have invented a new and useful Improvement in Manifold-Books, of which the following is a specification, reference being had therein to the accompanying drawings.

10 My invention relates to manifold books and particularly to that class of manifold books comprising a cover or holder and a separable or removable pad or body of leaves such as are used for salesbooks, order books 15 and similar purposes, in which the covers are used continuously and the pads renewed when used up.

Heretofore in the use of such books, it has been customary to provide a carbon sheet 20 which has generally been pasted or secured at one edge to the edge of a piece of heavier cardboard or paper stock such as tag-stock, the latter being inserted between the back of the pad of leaves and the cover and the 25 former being turned over and inserted between the top leaf of the pad and the leaf next underneath. After the carbon sheet has been used up it and the tag-stock holder are thrown away. This practice involves 30 the operations of cutting the tag-stock the desired size and pasting the carbon sheets thereto and later the waste of the tag-stock.

The main object of my invention is to provide a manifold book in which the cover 35 has permanent provision for removably holding a carbon sheet.

Another object of the invention is to provide holding means which is efficient and simple in construction and operation so that 40 the carbon sheet is held at all times securely against displacement and yet may be easily and expeditiously inserted and removed.

A further object is to eliminate the process of pasting the carbons to the sheets of 45 tag-stock and the waste of that stock and thereby reduce the cost of production of such books.

Other objects of the invention will be more specifically described and pointed out hereinafter.

In the accompanying drawings illustrating the preferred embodiment of my invention, Figure 1 is a view in perspective of a manifold book embodying my invention, the 55 cover being shown in an open position and a portion of the top leaf of the pad being

cut away to show the carbon sheet; Fig. 2 is a cross-sectional view on line 2—2 in Fig. 1; Fig. 3 is a plan view of the means for holding the carbon sheet and a portion of 60 the cover adjacent thereto showing the carbon sheet in position; Fig. 4 is a plan view, on an enlarged scale, of one means for fastening the holding means and Fig. 5 is a longitudinal view on line 5—5 in Fig. 4. 65

Referring to the drawings and particularly to Fig. 1, 10 designates the holder or cover of the book which may be made of various material, such as cardboard, leather or cloth or of metal covered with leather or 70 cloth. As shown the cover is made double with two leaves 10 and 12 united by flexible material 14 which acts as a hinge, but if desired, the cover 10 may be secured singly.

16 represents a pad or body of leaves 75 bound together at one end by wire stitching (not shown) or in any other suitable manner. The pad may be made up in any suitable manner but is generally composed of original and duplicate sheets alternating, 80 the original sheet receiving the writing which is transmitted to the duplicate sheet by a carbon interposed between the two. The cover 10 is provided with any suitable means for holding the pad such as a spring clamp 85 18 of well known form permanently fastened to the cover. The clamp 18 is opened up to permit the insertion or removal of a pad through the medium of a turned-up portion or finger-piece 20. To prevent lateral 90 displacement of the pad and to protect the carbon sheet 22, the cover 10 may be provided with an upright flange 24 extending partially along one side.

The main feature of my invention resides 95 in the provision of means permanently secured to the cover for holding the carbon sheet and in the drawings is shown one form of this means. Two spring strips 26 and 28 are fastened to one end thereof in a superposed relation to the cover 10 at or near the top by eyelets 30, 30, or in any other suitable manner. The spring strips may be made of steel, whalebone, composition or other material which is flexible and which, 100 when bent and released, will return to a normal, straight position. The carbon sheet is inserted at one edge between the two strips 26 and 28 and is held by them.

If desired, means may be provided for 110 locking the ends of the strips 26 and 28 together and the use of such means may be

found necessary in connection with books of extreme length employing a comparatively long and narrow carbon sheet. Various means may be utilized for this purpose 5 and one such means is shown in the drawings comprising a tongue and slot arrangement. Near its free end, the strip 28 is provided with a struck up tongue 32 and the strip 26 with a rectangular slot 34 of a 10 dimension sufficiently large to receive the tongue 32. The slot 34 is so located (see Fig. 5) that the tongue 32, when in the slot, overlaps and holds down the end of the strip 26.

15 The locking or unlocking of the strips is easily accomplished by merely bending the two strips upwardly together until the tongue on the strip 28 registers with the slot in the strip 26, when, if they are to be 20 locked together they are pressed together and returned to a straight position under pressure, or if they are to be unlocked, they are then separated.

In the use of my book the carbon sheet 25 22 may be arranged in the holding means either before or after the pad 16 has been placed in the clamp 18, but if the pad is present, it is merely turned upwardly and toward the part 12 of the cover in order 30 to give access to the holding means. The strips 26 and 28 being unlocked are separated and the edge of the carbon sheet is inserted between the two strips which are then pressed together and locked by bending 35 or in any other suitable manner. After the edge of the carbon sheet is locked, the body of the sheet is then turned back over the top strip 26 and the pad 16 is then inserted in the clamp or if present is turned 40 downwardly upon the cover 10 and the body of the carbon sheet is laid between the top leaf of the pad and the leaf next underneath. After the top leaf has been written upon and the writing reproduced on the 45 duplicate sheet through the medium of the carbon sheet, the two leaves are then separated from the pad at the perforated line 36. The third sheet of the pad which has then become the top sheet is lifted up and 50 the carbon sheet dropped upon the next sheet which originally was the fourth sheet and the top sheet is then returned to a flat position on the carbon. This process is repeated until the pad is entirely used up when 55 the stub of the pad is removed from the clamp 18 and a new pad inserted. When the carbon sheet is used up, the two strips 26 and 28 are unlocked, the carbon removed 60 and a new carbon inserted and the strips locked.

It will be observed that in practice, the carbon sheet is also held to some extent by the pad itself, since the carbon is folded back over the strip and is held by the weight

of the pad. I have found that in books 65 of short length, the carbon sheet is held securely by the strips 26 and 28 without requiring locking means but for books of greater length the locking means are desirable and insure a perfect hold. 70

The use of my invention has the advantage of providing positive means for holding the carbon sheet in a manifold book in proper relation at all times with the pad and thereby insures the securing of good carbon 75 copies on the second sheets. It also entails a considerable saving in labor and material since the tag-stock and the pasting of the carbon sheets thereto are entirely eliminated.

What I claim is:—

1. A cover for a manifold book provided with means for holding a pad of leaves and with a pair of flexible strips secured together and to said cover at one end thereof and adapted to hold one edge of a carbon sheet between them, one of said strips having a recess adjacent its free end and the other of said strips having a struck up tongue adjacent its free end adapted to engage said recess for locking the two strips 90 together. 80

2. A manifold book having, in combination, a cover, a clamp secured to said cover, a pad of leaves held at one end by said clamp, a pair of flexible strips for holding 95 one edge of a carbon sheet between them, said strips being secured together and to the cover at one end thereof, said strips being so located as to be underneath said pad when said pad is in its normal position and 100 a carbon sheet having one end held between said two strips, said carbon sheet being turned over between said strips and said pad then up over one edge of said pad in position to be interposed between the adjacent 105 leaves of said pad.

3. A manifold book having, in combination, a cover, a pad of leaves, means for removably securing said pad within said cover and a pair of thin flexible strips arranged 110 between said pad and cover for holding one edge of a carbon sheet between them, said strips being secured together and to the cover at one end only thereof.

4. A manifold book having, in combination, a cover, a clamp secured to said cover, a pad of leaves removably held at one end by said clamp and a pair of flexible strips for holding one edge of a carbon sheet between them by friction; said strips being 115 secured together and to the cover at one end only thereof and being so located as to be underneath said pad when said pad is in normal position in said cover. 120

In witness whereof I hereunto set my hand this seventh day of July, 1919. 125

CHARLES W. POTTER.
